Attorney

UNITED STATES PATENT OFFICE.

ELMER O. NELSON, OF HATTON, NORTH DAKOTA.

LOADING APPARATUS.

Application filed April 9, 1921, Serial No. 459,938. Renewed May 15, 1923.

To all whom it may concern:

Be it known that I, ELMER O. NELSON, a citizen of the United States, residing at Hatton, in the county of Traill and State of North Dakota, have invented certain new and useful Improvements in Loading Apparatus, of which the following is a specification, reference being had to the accompanying drawings.

10 This invention relates to certain improvements in loading apparatus, and it is primarily an object of the invention to provide a device of this general character whereby manure or kindred material may be collected from a pile or the like and discharged within the body of a manure spreader or other vehicle.

It is also an object of the invention to provide an apparatus of this general character including a portable body provided with a laterally disposed elevator adapted to discharge within the body of a manure spreader or other vehicle, together with a rotary element for throwing manure or the like from a pile to the elevator.

20 The invention consists in the details of construction and in the combination and arrangement of the several parts of my improved loading apparatus whereby certain important advantages are attained and the device rendered simpler, less expensive and otherwise more convenient and advantageous for use, as will be hereinafter more fully set forth.

25 The novel features of my invention will hereinafter be definitely claimed.

In order that my invention may be the better understood, I will now proceed to describe the same with reference to the accompanying drawings, wherein:

Figure 1 is a view in side elevation illustrating a loading apparatus constructed in accordance with an embodiment of my invention;

45 Figure 2 is a fragmentary transverse sectional view taken through the elevator mechanism as herein included;

Figure 3 is a view in top plan of the structure as illustrated in Figure 1;

50 Figure 4 is an enlarged fragmentary vertical sectional view taken through the forward portion of the body illustrating in detail the means herein embodied for raising

and lowering the forward portion of the machine;

55 Figure 5 is a fragmentary view in end elevation of the rotary element, said end being opposite to that shown in Figure 1; and

Figure 6 is an enlarged fragmentary view 60 partly in elevation and partly in section of the structure shown in Figure 5.

As disclosed in the accompanying drawings, B denotes the body of my improved apparatus, said body including a rear portion X and a forward portion Y arranged below the rear portion X and in relatively close proximity to the surface upon which the apparatus is supported. The rear portion X is supported by the tractor wheels W 70 while the forward extremity of the front portion Y is supported by the steering wheels S.

The steering wheels S are operatively supported by a yoke 1 provided with an upstanding shank 2 extending through the forward extremity of the forward portion Y of the body B and said shank is provided lengthwise thereof with the annular teeth 3 with which engages a gear 4 so that upon 80 requisite rotation of said gear, the forward portion Y of the frame may be raised or lowered as the necessities of practice may require.

Also keyed to the shank 2 is a worm gear 85 5 or the like, the connection between the gear 5 and the shank 2 permitting the gear to have movement lengthwise of the shank. A suitable steering rod 6 is operatively engaged with the gear 5 so that the shank 2 90 may be rotated as desired to control the direction of travel of the body B. Operatively engaged with the gear 4 is a rod 7 upon requisite rotation of which the gear 4 will be caused to effect the desired raising or lowering of the forward portion Y 95 of the body B.

E denotes an elevating mechanism carried by the forward portion Y of the body B and which includes the endless 100 member 8 traveling in a direction transversely of the body B with one end portion extending upwardly and laterally from the body B on a predetermined incline, the upper end of the inclined portion terminating 105 in the discharge end of the elevator mecha-

2
nism E so that the material carried thereby may be discharged into the body of a manure spreader or other vehicle which may be positioned below said inclined portion 5 of the elevator mechanism.

Supported by the body B, or more particularly by the forward portion Y thereof in advance of the lower or horizontal portion of the elevator E but in close proximity thereto, is a rotary element R. The element R embodies the heads 9 suitably fixed and positioned upon a shaft 10 rotatably supported by the body B. The peripheral portions of the heads 9 are connected by the bars or slats 11 spaced apart a desired distance circumferentially of the heads 9 and radiating from said bars or slats 11 are the fingers or prongs 12.

Fixed to the shaft 10 is a sprocket 14 around which passes an endless chain 15, said chain also passing around a relatively large sprocket 16 carried by a shaft 17. The shaft 17 is supported by the central portion of the body B and extends transversely thereof and also fixed to said shaft 17 is a pulley 18 in driven connection by the belt 19 with a motor or engine M carried by the rear portion of the body B, said motor or engine being of any desired character, but preferably of an internal combustion type.

The shaft 17 is rotated in a direction by the motor or engine M to cause the lower stretch of the chain 15 to move forwardly so that the element R will be rotated in a direction and at such speed to engage the manure or other material in the pile and throw the same upwardly and rearwardly upon the lower horizontal portion of the elevator E. Coacting with the upper stretch of the chain 15 at a desired point between the sprockets 14 and 16 is a guide sprocket 20 and which sprocket particularly serves to hold the forward portion of the upper stretch of said chain below the adjacent end of the elevator E so that said chain will offer no hindrance or obstruction to said elevator.

Fixed to one of the wheels W is a relatively large sprocket 21 around which passes a chain 22 which is also disposed around a smaller sprocket 23 fixed to a countershaft 24. The countershaft 24 is supported by the brackets 25 depending from the rear portion X of the body B. The countershaft 24 has also fixed thereto a pulley 26 of a radius greater than the radius of the sprocket 23. Passing around the pulley 26 is a cross belt 27 which also passes around a pulley 28 fixed to the shaft 17. The chain 22 and the belt 27, together with the coacting sprockets and pulleys, provide means whereby the apparatus may be driven forwardly by the motor or engine M and the ratio of the sprockets 21 and 23 and pul-

leys 26 and 28 is such to cause the body B to move forwardly at an extremely slow speed so that the advance of the apparatus will not interfere with the requisite discharge by the element R of the manure or kindred material upon the lower or horizontal portion of the elevator E.

As herein disclosed, the pulley 28 is loosely mounted upon the shaft 17 and is provided with a clutch face 29 with which coacts in a conventional manner a clutch member 30 keyed to the shaft 17 for rotation therewith but capable of movement longitudinally of said shaft. By this means, the element R may be driven, when desired, with the body B at a standstill.

The sprocket 20 is fixed to a shaft 31 extending transversely of the body B and supported thereby. The shaft 31 is operatively engaged, as at 32, with the operating shaft 33 for the endless member 8 comprised in the elevating mechanism E.

The end portion of the shaft 10 at the left side of the machine or at the side remote from the elevator mechanism E is supported by a bearing 34 carried by an arm 35 depending from the adjacent side member of the body B. The upper portion of the arm 35 is outwardly offset, as at 36, and passing over said offset portion 36 are the extended extremities of the bars or slats 11. Said extended portions of the bars or slats 11 are provided with the outwardly inclined fingers or prongs 12'. The right hand end portion of the shaft N is supported by an underhung bearing 10' as illustrated in Figure 1 of the drawing.

As the machine advances, the fingers or prongs 12' engage the pile and result in sufficient clearance to one side of the machine to facilitate its advance during a working operation.

From the foregoing description it is thought to be obvious that a loading apparatus constructed in accordance with my invention is particularly well adapted for use by reason of the convenience and facility with which it may be assembled and operated, and it will also be obvious that my invention is susceptible of some change and modification without departing from the principles and spirit thereof and for this reason I do not wish to be understood as limiting myself to the precise arrangement and formation of the several parts herein shown in carrying out my invention in practice except as hereinafter claimed.

I claim:

1. An apparatus of the class described comprising a portable body, an underhung frame carried thereby, an elevator moving transversely of the underhung frame and discharging above and to one side of the bottom, a rotary element provided with material engaging means, said element being

- positioned in advance of the frame, one end portion of the means carried by the frame for rotatably supporting an end portion of the element, a bearing depending from the body for supporting the opposite end portion of the element, and means for rotating the element in a direction to cause said element to throw material upwardly thereover and back upon the elevator.
- 6 2. An apparatus of the class described comprising a portable body, an underhung frame carried thereby, an elevator moving transversely of the underhung frame and discharging above and to one side of the
- 10 bottom, a rotary element provided with material engaging means, said element being positioned in advance of the frame, one end portion of the means carried by the frame for rotatably supporting an end portion of the element, a bearing depending from the body for supporting the opposite end portion of the element, means for rotating the element in a direction to cause said element to throw material upwardly thereover and back upon the elevator, the bearing for the rotary element depending from the body having its lower portion offset inwardly of the central portion of the rotary element, the adjacent end portion of the rotary element being provided with outwardly inclined fingers.
- 15 In testimony whereof I hereunto affix my signature.

ELMER O. NELSON.
